UNITED STATES PATENT OFFICE

100,599

DESIGN FOR AN AUTOMOBILE BUMPER GUARD

Ray J. Fitness, Lansing, Mich., assignor to Reo
Motor Car Company, a corporation of Michigan

Application September 16, 1935, Serial No. 58,570

Term of patent 3½ years

To all whom it may concern:

Be it known that I, Ray J. Fitness, a citizen of the United States, residing at Lansing, in the county of Ingham and State of Michigan, have invented a new, original, and ornamental Design for an Automobile Bumper Guard, of which the following is a specification, reference being had to the accompanying drawing, forming a part thereof.

Fig. 1 is a front elevational view of an automobile bumper guard showing my new design; and—

Fig. 2 is a side elevational view thereof.

I claim:

The ornamental design for an automobile bumper guard, as shown.

RAY J. FITNESS.
